UNITED STATES PATENT OFFICE.

FREDERICK S. ANABLE, OF BOSTON, MASSACHUSETTS, ASSIGNOR TO NATIONAL BINDING MACHINE COMPANY, OF NEW YORK, N. Y., A CORPORATION OF NEW YORK.

STRIP-SERVING DEVICE.

1,191,056.

Specification of Letters Patent. Patented July 11, 1916.

Application filed January 10, 1908. Serial No. 410,098.

To all whom it may concern:

Be it known that I, FREDERICK S. ANABLE, a citizen of the United States, residing at Boston, in the county of Suffolk and State of Massachusetts, have invented an Improvement in Strip-Serving Devices, of which the following description, in connection with the accompanying drawings, is a specification, like letters on the drawings 10 representing like parts.

This invention relates to devices or apparatus for supplying strips of paper or other suitable material of any desired length to be applied to packages, bundles, bottles or 15 any other suitable use, the illustrated embodiment thereof showing an apparatus provided with means for holding a strip-supply previously gummed on one side, such strip being adapted to be withdrawn in selected lengths, and further provided with 20 means for moistening the gummed side of the strip as the latter is withdrawn. It is apparent that an ungummed strip of paper or the like might be employed and the 25 moistening device be utilized for applying adhesive to the side of the withdrawn strip.

My invention will be best understood by reference to the following description when taken in connection with the accompanying 30 illustration of one specific embodiment thereof, while its scope will be more particularly pointed out in the appended claims.

In the drawings: Figure 1 is an elevation 35 showing a strip serving apparatus embodying one form of my invention; Fig. 2 is a plan view of a portion thereof, on an enlarged scale; Fig. 3 is a section on the line 3—3 looking toward the severing device and 40 with certain parts removed; Fig. 4 is a side elevation of the moistening, severing and guiding means on an enlarged scale; Fig. 5 shows a modified arrangement of moistening device; and Fig. 6 shows a further modification.

Referring to the drawings and to the embodiment of my invention therein shown, there is provided suitable means for holding a strip supply, herein a cylindrical 50 holder 1 within which a roll of gummed strip paper or tape is revolvably mounted upon a spindle. Any suitable tension means may be employed to impart suitable tension to the strip during delivery thereof, the 55 strip, being adapted to be unrolled or with-

drawn from the roll as represented in the drawings, passing out beneath the guide roll 2. The holder is mounted upon a suitable base 3 and kept in suitable operative relation to the various coöperating devices, all 60 of which are mounted on the frame-work 4.

In the illustrated embodiment of the invention the arrangement of the coöperating elements is such that the operator may seize the free end of the strip and, drawing the 65 gummed side thereof over and in contact with a suitable moistening device may then sever a selected length thereof by drawing the strip into contact with suitable severing means. It is obvious that any suitable 70 mechanism may be employed to accomplish this result. In the illustrated form of the invention in Fig. 1, I have shown a moistening device in the form of a roller 5 journaled in the frame-work 4 and partly immersed within the reservoir 6, the latter containing water or adhesive according as a 75 gummed or ungummed strip is employed. The roller may be covered with any suitable absorbent material, such as flannel 80 cloth or the like, and, in place of the roller, a stationary pad or wicking or the like, or other suitable moistening means may be employed.

Coöperatively arranged relatively to the 85 moistening roller 5 is suitable severing means, the same herein comprising a severing blade 7, against the edge of which the strip is adapted to be drawn for severing. This blade may be placed in any suitable 90 position, but herein the same is secured upright and fixedly to the frame-work 4. Its position may be inclined to the normal plane of the strip, and herein is shown as at substantially right-angles thereto, so that, in 95 order to engage the cutting edge of the knife, the strip may be lifted and turned or partly turned about one edge through an angle of approximately 90°. The severing blade is positioned above the service path of 100 the strip, so that to sever the strip the latter is deflected upwardly from its service path by the operative after the desired length of strip has been drawn from the strip roll in contact with the moistener. In 105 other words, the moistener and the severing blade are upon opposite sides of the service path of the strip, so that the strip end is swung upwardly for severance, after 110 which the free end of the strip drops from

engagement with the severing blade toward the moistener, but not into moistening relation therewith, and remains with its free end projecting into space in proximity to the moistener and in position permitting its free end to be readily grasped for further draft.

To prevent accidental injury to the severing knife or contact therewith on the part 10 of the operator, there is preferably, though not necessarily, provided guarding means which normally cover or protect the said knife, but which may be withdrawn automatically on movement of the strip itself 15 toward a severing position. To accomplish this, there is provided the sheath 8 having a U-shaped cross section which may be swung up from the side substantially to cover the knife or withdraw from it at will. This 20 sheath is secured to the rock shaft 9 journaled on the frame-work, and connected at its opposite end to the forked or slit guide 10 through the open slit of which the strip rests and through which the same is drawn as the 25 operator extracts a strip section from the apparatus. When the operator lifts the strip to turn the same against the severing knife, the guide 10 is also lifted and turned with the result that the sheath 8 is thrown 30 back by the rock shaft 9 away from the knife, thereby clearing the latter for free unimpeded cutting contact with the strip, thus permitting the latter to be severed without obstruction from the sheath. In other 35 words, the sheath is automatically withdrawn through initial severing movement. The severing blade or knife is here shown as extending substantially radially to the moistener roll 5. The unsevered or remaining 40 section of the strip is immediately returned to its normal position by the guide 10 through the action of the spiral spring 11 attached to the rock shaft. The strip severing blade 7 is arranged substantially radially 45 with respect to the moistening means and as positioned permits the return of the free end of the strip after severance to a position in close proximity to but out of contact with the moistening roller 5. This 50 described positioning of the blade permits the strip to be severed along a line normal to the edges of the strip. Moreover, it will be observed that the strip severing blade is laterally beyond but is closely adjacent one 55 lateral edge of the strip. This positioning of the blade permits the lateral deflection and turning of the strip for severance.

It is obvious that guarding means might be employed in combination with severing 60 devices of other construction and location than the specific one here shown, and that the severing device might be freed from the obstruction of the guard either by its own movement or by the combined movement of 65 the guard and the severing device, or in

various other ways which it is not here necessary to specify, all being within the broad and contemplated scope of this invention.

The movement of the strip toward a position of severance causes the same, in that specific form of my invention here selected for illustration, to assume a turned or partly turned position under strain, producing a tendency to tear the strip at some point in its length. Such tear or rupture would obviously tend to start along that edge of the strip which is lifted. In order to distribute the strain evenly to the strip when turned or partly turned, so that the strip will be drawn firmly across the severing knife without danger of rupture in any other point in its length, there is preferably provided guiding means which will present a coöperating guiding surface conforming to the strip in its turned or partially turned position and thereby distribute the strain evenly thereto.

The character or form of the coöperating guiding surface will, of course, depend upon the position of the severing blade with respect to the service path of the strip. In any form of my invention, the coöperating guiding surface, of suitable form, is upon the opposite face of the strip from the moistener; that is, it is at the ungummed face of the strip and extends transversely of the strip and is so positioned that the ungummed face of the strip contacts with the said coöperating guiding surface during the severing operation. In the present instance, such guiding means is illustrated in the form of a cone-shaped guiding roller 12, suitably located between the severing device and the holder, and journaled upon the frame-work so that the strip is caused to pass beneath the same. The said roller is arranged with its smaller end or diameter over the edge of the strip which is to be lifted at the time of severance, so that when so lifted against the knife, when the latter is positioned as here shown the strip will contact with the face of the roller and be permitted the half turn necessary to sever the same without producing undue strain upon the strip or disturbance thereof within the holder, or at any other point along its length.

Obviously other devices than the cone-shaped roller 12 may be employed for performing the intended function in the combination shown, and a device of this character for evenly distributing the strain in a tensioned and turned or partly turned strip has useful and novel application to strip serving devices outside of the particular combination herein shown and although the strip may be kept in continuous turned condition and in constant contact with the guiding means. In other words, I regard such guiding means within my invention irrespective of the specific form of apparatus

herein shown or the particular location or construction herein described of the severing means or other elements herein disclosed, or the fact that the strip is brought into contact with the said guiding means intermittently only in that embodiment of my invention herein illustrated.

It will be observed that the frame-work 4 carries a wall 13, between which and the 10 guide rollers 2 and 12 the strip is caused to pass. This wall is preferably extended beneath the slit guide 10 and over the mid portion of the moistening roller 5 as shown, or such other means or construction of said 15 wall are preferably adopted that the unsevered and remaining portion of the strip will be kept out of contact with the moistening roller. In the present instance, the severing knife is located directly over and above the 20 mid portion of the moistening roller and in such relation to the roller and the end or lip of the wall 13 that the strip when lifted and turned will be severed along a line which separates the unmoistened area of the strip 25 and the moistened area thereof, so that only the portion to be severed will be moistened, the unsevered or remaining portion being returned by the slit guide 10 to rest loosely over the wall 13 and in a position where it 30 can be readily seized by the operator for the extraction of an additional selected length when desired. It is obvious that the moistening of the severed portion of the strip only may be obtained in various other ways 35 than that herein described; also that the severing means may be caused to move against the strip instead of the strip against the severing means, or that both may undergo movement, or that other constructions of 40 severing means and moistening means than the specific ones herein shown may be employed without departing from the spirit of the invention.

It will be evident not only that the strip 45 is severed at the rear limit of the moistened area, so that the unsevered portion of the strip is unmoistened, but that the strip is drawn in a straight line from the strip roll or from the guide roll 2 to and across the 50 moistener, and that the free end of the strip after severance is prevented from dropping into contact with the moistener. Furthermore the free end of the strip, after severance is readily accessible to the fingers and 55 thumb of the user. The strip roll is itself upright, and when the severing blade is so positioned as to require turning of the strip to bring the latter into severing relation therewith, as represented in this form of my 60 invention, the free end of the strip after severance is at once automatically returned to a flat or normal position, so that the strip extends in an untwisted condition or normal condition from the strip roll to its 65 free end. Moreover the draft upon the strip

in the serving operation is directly outward from the strip roll, or in other words, the pull upon the strip is straight from the point of delivery of the strip from the roll, and in drawing the strip outward across the 70 moistener the strip is not twisted. If desired, and as shown, the wall 13 slopes upward from the strip roll substantially to the moistener, the forward edge of said wall extending to such point as to insure the free 75 end of the strip, after severance, being positioned out of contact with the moistener until further draft upon the strip is made. In the present form of my invention, I have in Figs. 1, 2 and 4, shown the forward edge of 80 the wall as sufficiently prolonged to overlie slightly the rear portion of the moistener, though obviously the extent of the wall forward may be varied within the scope of my invention, so long as the purpose is effected 85 of preventing contact of the strip with the moistener after severance and before further draft upon the strip. The upward slope of the wall 13 permits the employment of a moistener and tank or reservoir of sufficient 90 capacity to avoid constant or very frequent refilling, while permitting the strip roll to be supported low, thus rendering the whole device compact. But more important than this, the upward slope of the wall 13 95 with the consequent direction of movement of the strip followed by the outward moistener-contacting travel of the strip insures an effective moistening contact of the strip with the moistener without excessive downward deflection of the strip. It will be further noted that the strip contacts flatwise with the wall 14 from a point close to the strip wall substantially to the moistener and that the strip guiding means overlies 100 the wall 13 between the strip roll and the moistener.

In Fig. 5, I have shown, in place of the moistening roller 5, an arch shaped wick 14 having its depending ends immersed within 110 the liquid of the tank 6 and presenting a moistened area over which the strip is adapted to be drawn, as in the case of the roller in Fig. 5. Although the inclosing and protecting wall 13 is shown in Fig. 5 as terminating over the mid portion of the arch, so that the overlying strip is moistened up to the point of severance only, the wall may be terminated somewhat short thereof, so that the portion of the wick shown in Fig. 115 5 as underlying the end of the wall 13 may be available to contact with the length of strip which is withdrawn and thereby more effectively moistens the side thereof. In other words, the lip or forward edge of the 120 wall 13 may overlie the wick 14 to any desired extent or may be terminated at the rear edge of such wick or short thereof. In such case, obviously a portion of the strip remaining would be slightly moistened, 130

although if it is desired to sever the strip substantially at the limit of the moistened area, the wick or roller might still be located as represented in Fig. 6, so that a larger portion or area of the wick or roller than shown in Fig. 1 is available for moistening, while the severing device, being located at the point where contact with the moistening element begins, is still effective for severing 5 along the line which separates the moistened from the unmoistened portion.

It will be obvious that the specific construction as well as the relative location of the parts herein shown may be extensively 10 varied without departing from the spirit of my invention, the detailed construction herein shown being submitted for the sole purpose of presenting one specific type or embodiment of my invention without intent or purpose to limit the same to the one 15 form herein shown.

Claims:

1. A strip serving apparatus comprising in combination, strip holding means, strip 20 moistening means in the service path of the strip, strip severing means, and a cone-shaped guiding roller extending transversely of the service path of the strip and having one end at least spaced therefrom, the strip 25 being deflectable against said roller in the severing operation.

2. A strip serving apparatus comprising in combination, strip holding means, strip moistening means in the service path of the 30 strip, strip severing means angularly positioned with respect to the normal service path of the strip, and strip guiding means extending transversely of and inclined to the normal service path of the strip, the latter 35 being supported against said guiding means during severance.

3. A strip serving apparatus having means for holding a strip from which the latter 40 may be drawn in a turned or partly turned 45 condition, a tapering roll for guiding the strip, a strip severing blade adjacent the service path of the strip, the roller being located relatively to the blade to support the strip during severance, and strip moistening means.

4. A strip serving apparatus having means for holding a strip from which the latter 50 may be drawn in a turned or partly turned condition, a tapering roller for guiding the strip, a substantially upright strip severing 55 blade adjacent the service path of the strip, the roller being located relatively to the blade to support the strip during severance, and strip guiding means.

60 5. A strip serving apparatus having a support for a strip adapted to be drawn therefrom, said support being shaped to permit the temporary turning of the strip after leaving the holder and the return of 65 the strip to its former unturned position,

means inclined to the service path of the strip for guiding the strip at or about the region of turn thereof to distribute the strain evenly throughout, and moistening means positioned in the direct service path 70 of the strip to moisten the strip when it has been turned back to its said former unturned position.

6. A strip serving apparatus having a support for a strip adapted to be drawn therefrom, said support permitting the temporary turning of the strip after leaving the holder and the return of the strip to its former unturned position, means inclined to the service path of the strip for guiding 75 the strip at or about the region of turn thereof to distribute the strain evenly 80 throughout, a severing blade positioned to sever the strip when in turned position, and moistening means in the normal service path 85 of the strip and against which the strip is adapted to be drawn when in unturned position.

7. In a strip severing apparatus, the combination with strip holding means of strip 90 moistening means so positioned with respect thereto as to permit the moistening of the strip when in unturned position, intermediate guiding means, and strip severing means positioned laterally beyond the service path of the strip and angularly directed with respect thereto, thereby to require 95 turning of the strip for severance thereagainst.

8. In a strip severing apparatus, the combination with strip holding means, of substantially cylindrical strip moistening means in the service path of the strip, and a strip severing blade having its body and edge in a plane extending outwardly from the moistening means and substantially radial with respect to said moistening means.

9. A strip serving apparatus having strip holding means and a support constituting a path along which the strip may be served, 110 strip severing means at an angle to the normal plane of the strip when upon said support, and a strip guiding device intermediate the severing means and the holding means and presenting a strip guiding surface conforming to the strip when turned from its normal path, the said strip guiding device being positioned with respect to the support to permit turning of the strip to its normal path for severance.

10. In a strip serving apparatus, the combination with strip holding means of a strip moistening roller arranged in the service path of the strip, and a strip severing blade closely adjacent said roller and arranged substantially radially with respect thereto, thereby to compel turning of the strip thereagainst for severance.

11. A strip serving apparatus having strip holding means from which the strip is adapted 130

to be drawn by the fingers of the operator, an inclined strip support leading from said strip holding means, moistening means operatively related to said support and strip severing means above the moistening means and the strip support and against which the strip is adapted to be deflected for severance, the relative position of the severing means strip support and moistening means being such that after severance the strip is supported out of contact with the moistener, and the severing means and strip support being in such relative position that the free end of the strip substantially coincides with the forward edge of the strip support after strip severance.

12. A strip serving apparatus comprising in combination, strip holding means, a strip moistener in the normal service path of the strip, and a strip severing blade laterally beyond the service path of the strip adjacent to one lateral edge of the strip and having its severing edge at an angle with respect to the normal service path of the strip.

13. A strip serving apparatus having strip holding means from which the strip is adapted to be drawn, strip moistening means, and a strip severing blade positioned laterally beyond the service path of the strip and against which the strip is adapted to be deflected laterally for severance.

14. A strip serving apparatus having strip holding means from which the strip is adapted to be drawn, fixed strip serving means and movable strip guarding means normally guarding said strip but movable therefrom for strip severance, and strip moistening means.

15. A strip serving device comprising in combination, strip package supporting means, strip moistening means, strip severing means, strip guarding means for said severing means, and means between the strip and the guarding means and operatively connected to the latter and adapted to be engaged by the strip to expose the severing means.

16. A strip serving device comprising in combination package supporting means, strip moistening means, strip severing means directly over and close to the moistening means, guarding means for the severing means, and a device connected to the guarding means and adapted to be moved by the strip upon deflection of the latter to expose the severing means.

17. A strip serving apparatus comprising in combination, a strip holder, a strip support extending therefrom and along which the strip is served flatwise, a strip moistener, a strip severing blade at one side of the service path of the strip, and a guard for the blade normally positioned to guard the blade but relatively movable with respect thereto to permit exposure of the blade for severance of the strip.

18. In a strip serving apparatus, the combination of strip holding means, strip moistening means in the normal service path of the strip, strip severing means and strip guiding means transversely inclined to the normal path of the strip and spaced therefrom at one edge of the strip and against which the strip is drawn in the severing operation.

19. In a strip serving apparatus, the combination with strip holding means, strip moistening means, strip severing means, a slit guide for said strip, and means governed by said slit guide for rendering said severing means operative.

20. A strip serving apparatus comprising a holder, a strip support in advance thereof and along which the strip may be drawn flatwise, means for moistening the strip when flatwise thereon, and a severing blade angularly positioned with respect to said support at one side of the strip and against which the strip is adapted to be turned for severance, said blade being positioned to sever the strip at substantially the rearward limit of its moistened area.

21. A strip serving apparatus comprising a strip holder, a moistener in the service path of the strip issuing from said holder, a strip guiding support or wall overhanging said moistener and a strip severing blade positioned at substantially the forward edge of said wall or support, but above the same and against which the strip must be deflected for severance, thereby to leave the projecting, unsevered end substantially co-terminal with the front edge of the wall after strip severance.

22. A strip serving device comprising in combination, a holder for a strip roll and from which the strip may be manually drawn, a strip guiding plate extending from the holder and constituting a support along which the strip may be drawn flatwise therefrom, a moistening roller adjacent the forward end of said plate and across which the strip may be manually drawn for severance, said guiding plate underlying the strip from the holder to the moistening roller, and at its forward end overlying the latter, and a strip severing blade above the service path of the strip and positioned to sever the strip at substantially the rearward limit of its moistened area, and against which blade the strip is upwardly deflected for severance, the severing blade and the strip guiding plate being in such relative position that the free end of the strip substantially coincides with the forward edge of the strip-guiding plate after strip severance.

23. A strip serving apparatus comprising in combination a support for a gummed strip roll from which the strip may be manually drawn, a moistening roller mounted for rotation in the service path of the

strip, a guiding plate underlying the strip and extending from substantially the strip roll forwardly with its free end overlying the rear portion of the moistening roller and 5 along which the strip may be drawn flatwise, said plate being positioned to leave the forward portion of the roller exposed to permit manual application of the strip end thereto, and a severing blade above the service 10 path of the strip and against which the strip is adapted to be upwardly deflected for severance, said severing blade being so located relative to the guiding plate that the strip may be severed thereby 15 along a transverse line that is adjacent to the free end of said guiding plate when the strip is resting thereon.

24. A strip serving device comprising in combination a strip roll holder or casing 20 from which the strip may be manually unrolled, a moistener constantly supported in the service path of the strip and across which the strip may be manually drawn for moistening, a strip guiding and supporting plate 25 extending along but underlying the service path of the strip and along which the strip may be drawn flatwise from the holder, said plate at its forward end extending into proximity to the moistener and supporting the 30 free end of the strip out of contact therewith after strip severance, and a strip severing blade higher than the service path of the strip but positioned to sever the strip at substantially the rearward limit of the moistened area and against which blade the strip 35 is upwardly deflected for severance, said severing blade and the guiding and supporting plate being relatively located in such position that after strip severance the free 40 end of the strip substantially coincides with the forward edge of the said plate.

25. A strip serving device comprising in combination a strip roll holder or casing from which the strip may be manually unrolled, a moistener constantly supported in the service path of the strip and across which the strip may be manually drawn for moistening, a strip guiding and supporting plate extending along but underlying the service 45 path of the strip and along which the strip may be drawn substantially flatwise from the holder, said plate at its forward end extending in proximity to the moistener and supporting the free end of the moistener out 50 of contact therewith after strip severance, strip guiding means above but close to said plate and between which and said plate the strip passes, and a severing blade higher than the service path of the strip but positioned to sever the strip at substantially the rearward limit of the moistened area and against which blade the strip is upwardly deflected for severance, said moistener and guiding and supporting plate being relatively located in such position that the free 55 end of the strip substantially coincides with the forward edge of the said plate.

26. A strip serving device comprising in combination a strip roll holder or casing 60 from which the strip may be manually unrolled, a moistener constantly supported in the service path of the strip and across which the strip may be manually drawn for moistening, a strip guiding and supporting plate extending along but underlying the service path of the strip and along which the strip may be drawn substantially flatwise from the holder, said plate at its forward end extending into proximity to the moistener and supporting the free end of the strip out of contact therewith but in proximity thereto after strip severance, and a strip severing blade higher than the service path of the strip and against which the strip is upwardly deflected for severance, said moistener and guiding and supporting plate being relatively located in such position that the free end of the strip, after strip severance, substantially coincides with the forward edge of said plate, the position of the severing blade with relation to the moistener being such that the strip is severed thereby at substantially the limit of the moistened strip area, thus leaving an un- 65 moistened strip end.

27. A strip serving device comprising in combination a strip roll holder or casing 70 from which the strip may be manually unrolled, a moistener constantly supported in the service path of the strip and across which the strip may be manually drawn for moistening, a strip guiding and supporting plate 75 extending along but underlying the service path of the strip and along which the strip may be drawn substantially flatwise from the holder, said plate at its forward end extending into proximity to the moistener and supporting the free end of the strip out of contact therewith but in proximity thereto after strip severance, and a strip severing blade higher than the service path of the strip and against which the strip is upwardly deflected for severance, said moistener and guiding and supporting plate being relatively located in such position that the free end of the strip, after strip severance, substantially coincides with the forward edge of said plate, the position of the severing blade with relation to the moistener being such that the strip is severed thereby at substantially the limit of the moistened strip area, thus leaving an un- 80 moistened strip end.

28. A strip serving device comprising in combination a strip roll holder or casing 85 from which the strip may be manually unrolled, a moistener constantly supported in the service path of the strip and across which the strip may be manually drawn for moistening, a strip guiding and supporting plate 90 extending along but underlying the service path of the strip and along which the strip may be drawn substantially flatwise from the holder, said plate sloping upward from substantially the strip roll to a point in proximity to the moistener and terminating at a slightly higher level than the upper face of said moistener, thereby upon strip severance to support the strip out of contact with but close to the moistener, strip guiding means above but close to the strip guiding plate and between which and said plate the strip passes, and a strip severing blade higher than the service path of the strip and against which the strip is upwardly deflected for severance, the position of said severing blade with respect to the moistener being such that the strip is severed thereby at substantially the limit of the moistened area.

29. A strip serving device comprising in combination, a strip roll holder, a moistener fixed in advance thereof in the service path of the strip, an upwardly inclined support extending from the holder to the moistener and along which the strip may be drawn substantially flatwise, the forward 95

end of the support terminating over the moistener but leaving the latter exposed, and a severing blade higher than the service path of the strip and against which the 5 strip is deflected for severance, the free end of the strip after severance being supported by the inclined support above and slightly out of contact with the moistener.

29. A strip serving apparatus having up-
10 right strip holding means from which the strip is adapted to be drawn by the fingers of the operator, a substantially straight strip support along which the strip is served when drawn from the holding means, strip
15 moistening means and strip severing means positioned laterally beyond the service path of the strip for severing the strip at sub-
stantially the limit of its moistened area, thus to leave no moistened end, the strip
20 moistening means being so located with re-
spect to the holding means and the strip support that the strip may be drawn from the holding means flatwise along said sup-
port to the moistening means.
25 30. A strip serving apparatus having strip holding means from which the strip is adapted to be served, moistening means, and strip severing means located between

the holding means and the moistening point at one side of the strip and normally 30 guarded from the strip but adapted to be exposed by service of the strip.

31. A strip serving apparatus comprising a strip support, a moistener in the service path thereof, a strip guiding wall over-
35 hanging a portion of said moistener, and a strip severing blade positioned at substan-
tially the forward edge of said wall later-
ally of the strip, thereby to sever the strip, so as to leave the projecting unsevered end 40 substantially coterminous with the front edge of said wall.

32. A strip serving apparatus comprising a strip support, a conical guide for the strip, a moistener in advance of said guide, 45 and strip severing means so positioned that the strip may be deflected into simultaneous engagement with the conical guide and severing means.

In testimony whereof, I have signed my 50 name to this specification, in the presence of two subscribing witnesses.

FREDERICK S. ANABLE.
